ATTORNEY.

UNITED STATES PATENT OFFICE.

WILLIAM S. MUNGER, OF LAWNDALE, CALIFORNIA, ASSIGNOR OF ONE-THIRD TO
TODD E. LACKYARD, OF LOS ANGELES, CALIFORNIA.

QUICK-ACTING VISE.

1,411,578.

Specification of Letters Patent.

Patented Apr. 4, 1922.

Application filed March 15, 1921. Serial No. 452,563.

To all whom it may concern:

Be it known that I, WILLIAM S. MUNGER, a citizen of the United States, residing at Lawndale, in the county of Los Angeles and 5 State of California, have invented new and useful Improvements in Quick-Acting Vises, of which the following is a specification.

It is the object of this invention to provide a device having improved means where- 10 by the moving jaw of the device may be quickly adjusted with relation to the stationary jaw and then moved into clamping engagement with the work by means of the usual operating mechanism.

15 The invention will be readily understood from the following description of the accompanying drawings, in which—

Figure 1 is a front elevation of a device constructed in accordance with the invention.

Fig. 2 is a side elevation of the same partly broken away.

Fig. 3 is a transverse section on the line 3—3 of Fig. 2.

25 The stationary jaw of the device may be mounted upon a suitable table or like support 1, and said jaw includes a usual base 2 secured to the support by means of bolts 3 and having the longitudinal bore 4 with the 30 jaw member 5 projecting from said base above the bore and at the front end of the base.

A support for the movable jaw of the device is received in bore 4 and is shown as a 35 bar 6 of sufficient length to permit of the desired adjustments of the movable jaw relative to the fixed jaw. The supporting bar is provided with recesses 7 along one face of the same, and a pin 8 received through the 40 base of the stationary jaw is adapted to engage in any one of said recesses for locking the supporting bar in adjusted positions relative to the jaw 5. The pin 8 may be provided with a usual operating head 9, and a 45 spring 10 preferably surrounds the shank of the pin and is held in position by a suitable threaded collar 11 so as to normally yieldably urge the pin into engagement with one of the notches 7. It will be understood that 50 by retracting the pin, the supporting bar 6

may be readily adjusted back and forth with relation to jaw 5.

The movable jaw of the device is carried by supporting bar 6 and includes a base 12 having a bore 13 in which the end of the 55 supporting bar is received, and a jaw 14 projecting from base 12 and co-operating with jaw 5 to form the device. The movable jaw is adjusted with relation to bar 6 by an operating connection comprising a bolt 15 ex- 60 tending into the bore of the movable jaw and retained in position by an end plate 16. The head of this bolt projecting outwardly from the movable jaw is provided with a usual operating rod 17 for turning said bolt. The 65 inner end of the bolt makes threaded engagement with a bore 18 in the end of supporting bar 6 so that rotations of the bolt will move the jaw 14 back and forth with relation to supporting bar 6.

In practice it will be understood that the movable jaw is first quickly adjusted with relation to the work to be clamped, by withdrawing pin 8 and sliding supporting bar 6 back or forth until the movable jaw is in approximate clamping position. The pin is then released so that its spring may project it into one of the notches 7 in order to lock the supporting bar with relation to the fixed 75 jaw, and the movable jaw is then clamped 80 against the work by adjusting said movable jaw with relation to the supporting bar through rotations of bolt 15.

Various changes may be made without departing from the spirit of the invention as 85 claimed.

What is claimed is:

A vise comprising a fixed jaw, a support 90 slideable through the base of the same toward and away from said jaw, means for retaining said support in adjusted positions comprising a co-operating pin and recesses upon said jaw and support, a moving jaw slideable upon said support, and operating means for said moving jaw including a threaded bolt 95 journaled in said moving jaw and engaging a co-operating threaded bore in said support.

In testimony whereof I have signed my name to this specification.

WILLIAM S. MUNGER.
